BRASSIÈRE CONSTRUCTION

Zelta M. Silva, Los Angeles, Calif., assignor to
Tichenor & Ferguson, Los Angeles, Calif., a
partnership composed of Colfax C. Tichenor, E.
Stirling Ferguson, and Mary L. Smith

Application February 25, 1946, Serial No. 649,834

2 Claims. (Cl. 2—42)

1

This invention pertains to an improved type of brassière which is adapted to suitably mold, support, and position the breasts of the wearer.

It is the general object of the present invention to disclose and provide a structure which will suitably mold and position the breasts without subjecting them to constrictive or flattening pressure. It is well known that well-developed or large breasts have a tendency to be brought into contact with and be flattened by most brassières so that the separate identity of the breasts is lost. The construction of the present invention, however, permits the separate identity of the breasts to be retained while at the same time suitable uplift and configuration is imparted. Moreover, these desirable results are attained by the use of limp, flexible, compliant materials and without the use of reinforcement, bones, stays, or other rigid, metallic or plastic inserts.

In addition, the brassière of the present invention may be readily made from a relatively small number of pieces so that the interior surface of the brassière has a minimum number of seams which may chafe the skin or render the brassière uncomfortable to the wearer.

It is an object of the present invention, therefore, to disclose and provide a simple, efficient construction for a brassière.

A further object of the invention is to disclose and provide a brassière provided with integral strap portions so arranged and positioned as to cooperate with a strap in imparting both upward and outward movement to the breasts of the wearer.

These and other objects of the invention will become apparent to those skilled in the art from the following description of an exemplary form embodying the construction embraced by this invention. In describing such exemplary form, reference will be had to the appended drawings, in which

Fig. 1 is a front view of the brassière in substantially the position assumed when the brassière is worn.

Fig. 2 is a horizontal section taken through the apex of the bust pocket of Fig. 1.

Fig. 3 illustrates pattern forms for the various sections or elements from which one of the breast-receiving cups of the brassière may be constructed.

Generally stated, the brassière of the instant invention includes a pair of preformed, breast-receiving pockets, a waist band and shoulder straps, as is customary in most brassières. By the term "preformed breast-receiving pockets" refer-

ence is made to the cups, each of which is adapted to receive and mold the breast. These pockets or cups are made of compliant, relatively limp, conformable, flexible material such as net, lace, and other fabrics or textiles, and the parts composing each cup are so formed and stitched that they assume a substantially conical or semi-spherical form, thereby more readily molding the bust without unnecessary or undesirable constriction or pressure thereagainst. The term "apex" as used hereinafter shall refer to that portion of the cup or pocket in which the nipple is ordinarily contained. The term "shoulder strap" as used hereinafter shall refer to any continuous or interrupted, adjustable or detachable, unitary or segmental strap member attached to the upper marginal edge of each breast-receiving pocket in a region above the apex thereof and adapted to extend over the shoulder for either permanent or removable connection with the waist band or a rearwardly extending portion of the brassière. The term "waist band" relates to that portion of the brassière which encircles the torso beneath the bust and which is generally provided with releasable connecting means at its ends so as to permit the garment to be tightly positioned around the body. Such waist bands may include one or more sections of elastic material. Waist bands are usually located at the lower edges of the under-arm and other portions of the brassière.

As shown in Fig. 1, the brassière of the present invention comprises two preformed, breast-receiving pockets 10 and 11, a waist band being indicated at the lower edge at 12. In the form of invention shown, the shoulder straps 13 and 14 are provided with suitable adjustment means in the rear portions thereof and include strap portions 15 and 16 which traverse the pockets 10 and 11 respectively. It will be noted that when the brassière is worn, the strap section 15 is carried by and traverses the opposing inner side 17 of the cup 10 in the region of the apex 18 of such cup. The strap section 15 also extends downwardly and outwardly to the lower and outer side of the cup and is shown merging with the waist band 12 at 19. The strap section 15 also extends upwardly and outwardly to above the apex 18 and to a zone of connection with the shoulder strap 13. The strap section 16 similarly but oppositely traverses the cup 11 so that the mid portions of the strap sections 15 and 16 partially cover the opposing inner sides 17 and 20 of the cups 10 and 11 respectively, whereas the lower portions of strap sections 15 and 16 diverge downwardly and out-

wardly and the upper portions of the strap sections diverge upwardly and outwardly.

It will be evident from the arrangement described that when the garment is worn, the tension on the shoulder straps 13 and 14 is transmitted to the strap sections 15 and 16 respectively and because of the angularity of the forces transmitted along the shoulder straps and strap sections, the breasts contained in the pockets 10 and 11 are separated and at the same time lifted and adequately supported.

A simple method of construction is attained by the use of patterns of the general configuration shown in Fig. 3. As there shown, the cup 10 may comprise an outer side section 21 having a substantially horizontal lower margin 22 adapted to cooperate with the waist band 12 and a generally V-shaped forward margin 23 with the point 18' of such forward margin materially above the lower margin 22. The side section 21 is also provided with an upper margin 24 which is virtually parallel to the lower margin 22 for a portion of its length and at about the level of the point 18', such upper margin 24 then curving upwardly to a point of connection or intersection 25 with the forward margin 23. The point 25 is preferably directly above the front end 26 of the lower margin 22, although it may be slightly forward of such front end 26.

The inner section 17 may be provided with a lower margin 27 adapted to cooperate with the waist band, an upper margin 28 inclined thereto and adapted to form the upper edge 28' on the inner side of the cup 10, a central margin (preferably concave) as indicated at 29, and a long forward margin 30, preferably including a concavity in its upper portion.

In the form of construction illustrated, the strap 13 and the strap section 15 are shown composed of a single strip of material 33 of virtually uniform width with the strength of the material, or weave, running longitudinally of such strap so as to be virtually non-yielding longitudinally. The lower edge of strap 33 is inclined as at 34, and one edge, as at 35, may be provided with a reverse curvature, the convex portion being capable of association with the concavity of the forward edge 30 of the inner section 17. Since the shoulder strap portion 13 is generally appreciably narrower than the strap section 15, it has been found desirable to employ a second element 37 similar in configuration to the lower portion of the element 33, the element 37 being of a length sufficient to cooperate with the lower portion of element 33 so as to act as a lining therefor throughout the area that the strap portion 15 traverses the pocket or cup 10.

The various elements 17, 33, and 21 are connected together so that the lower edges 22, 27, and 34 are in alignment, a separate waist band being attached to the lower portions of members 17, 33, and 21 for reenforcing purposes. The forward edge 23 is then connected to one edge of the element 33, whereas the forward edge 30 of element 17 is connected to the margin 35 of the element 33. It will be noted that the inner and outer sections 17 and 21 are separated and spaced from each other by the strap section.

A second cup having been made in a similar manner, the margins 29 of the corresponding inner sections 17 are suitably attached to each other and a pair of cups for the brassière are thus attained. It will be understood that suitable darts may be formed in the lower portion of

section 17 so as to give the desired fullness to the pocket.

Fig. 2 shows one manner in which the lining element 37 is attached to the lower portion of element 33 so as to form the strap section 15. Particular attention is drawn to the fact that at the zone of apex 18 the strap traverses the pocket as a part of the inner section and bears against the surface of the breast contained in such pocket. Obviously, however, minor shifts in position of such strap section, which do not destroy the efficacy and novel mode of operation of the structure are embraced by this invention.

Moreover, although the exemplary brassière has been described as made of two separate, opposing, inner sections 17 and 20, this centrally disposed area may be made of but a single piece of material.

It may be noted that the direction of the weave, or the direction in which the material is substantially non-yielding or nonstretchable, has been indicated in dash lines. For example, element 33 is substantially non-stretchable longitudinally, whereas element 21 is substantially non-stretchable in a direction parallel to the lower margin 22. It is also to be understood that the various margins of the completed brassière may be suitably stitched, taped, piped, decorated, etc. and the entire garment may be provided with a suitable lining.

All changes, and modifications coming within the scope of the appended claims are embraced thereby.

I claim:

35. 1. In a brassière made of flexible, compliant material and including a pair of preformed, breast-receiving pockets, a waist band and shoulder straps, the combination of: a strap section carried by and angularly traversing each breast-receiving pocket, each strap section traversing the upper portion of a pocket in a downward and inward direction from a zone of connection with a shoulder strap to a zone displaced inwardly from the apex of the pocket, then changing direction at said zone and traversing the lower portion of the pocket downwardly and outwardly to the waist band.

50. 2. In a brassière made of flexible, compliant material and including a pair of preformed, 55. 5. 3. In a brassière made of flexible, compliant material and including a pair of preformed, breast-receiving pockets, a waist band and shoulder straps, the combination of: a strap section carried by and angularly traversing each breast-receiving pocket, each strap section traversing the upper portion of a pocket in a downward and inward direction from a zone of connection with a shoulder strap to a zone displaced inwardly from the apex of the pocket, then changing direction at said zone and traversing the lower portion of the pocket downwardly and outwardly to the waist band, whereby the zone of connection of the lower end of said strap is displaced outwardly with respect to the zone in the region of the apex, each of said strap sections being substantially non-yielding longitudinally.
